UNITED STATES PATENT OFFICE.

GEORGE C. KNAUFF, OF CHICAGO, ILLINOIS.

WIRE-CONNECTOR.

1,101,939.

Specification of Letters Patent. Patented June 30, 1914.

Application filed February 17, 1913. Serial No. 748,841.

To all whom it may concern:

Be it known that I, GEORGE C. KNAUFF, citizen of the United States, residing at Chicago, in the county of Cook and State 5 of Illinois, have invented certain new and useful Improvements in Wire-Connectors; and I do hereby declare the following to be a full, clear, and exact description of the invention, such as will enable others skilled 10 in the art to which it appertains to make and use the same.

My invention relates to connectors for electric wires or cables and particularly to the class of connectors used on the lighting 15 circuits of automobiles.

It has been customary heretofore to depend upon the frictional engagement of slidable contacts for holding the parts of such connectors interengaged in effective 20 contacting relation, and in practice the jar-ring to which connectors are subjected upon automobiles has frequently loosened this frictional engagement, thereby rendering the connectors inoperative.

25 One object of my invention is to provide interengaging means independent of the contacts for maintaining the manually separable parts of the connector in effective contacting relation.

Another object is to provide simple means for detachably anchoring a wire terminal within the metal casing of a connector and for insulating the same.

A further object is to provide an elastic mounting for the contact carried by one of the connector members, whereby the contacts may aline themselves to insure good current-carrying connection in spite of irregularities in the size or shape of the 40 other portions of the connector members.

Other objects will appear from the following specification and from the drawings, in which:

Figure —1— is a view, partly in section 45 of a connector embodying my invention. Fig. —2— is a longitudinal section of the same with the two parts released from interengagement. Figs. —3— and —4— are end views of the connector parts.

50 In the embodiment shown in the drawings, the connector of my invention consists of two manually separable portions, each comprising a metal casing having a wire terminal mounted within the same, the terminals being preferably of the wire-wedging type shown and claimed in U. S. Letters

Patent No. 1018570, issued to me February 27, 1912. One of the manually separable portions comprises a substantially cylindrical casing 1 having one end turned inwardly 60 to form an annular flange 2 adapted to be clamped between an insulating bushing 3 and an insulating washer 4, through both of which latter the metal sleeve 5 extends when threadedly connected to a female contact tip 6. A screw 7 positioned axially of this contact tip is threaded into a screw eye 8, whereby the bared end 9 of an insulated cable 10 may be wedgingly secured between the eye of the said screw eye 8 and a tapering socket in the sleeve 5, after the method of the patent above cited.

The casing 1 preferably projects beyond the end of the female-contact tip, this end of the casing having diametrically opposite 75 longitudinal slots 30, each slot having a circumferential extension 29 terminating in an enlarged slot end or pocket 11. The said slotted end of the casing 1 is adapted to fit slidingly into the end of the bore of a metal cylinder 13 forming the casing for the other portion of the connector, which latter cylinder or casing has a pair of pins or projections 14 extending inwardly from opposite sides of the cylinder and adapted to interengage with the slots in the casing 1 after the manner of a so-called bayonet catch. Adjacent to its other end, the casing 13 has an inner groove 15 adapted to receive a split ring 16 of spring wire, the said groove being considerably less in depth than the diameter of the said wire. Interposed between the said ring 16 (which forms an easily removable but normally rigid, inwardly projecting flange or projection on the casing 13) and the inwardly directed projections 14, are two members adapted to slide freely within the casing 13 but normally held against the said ring and projections respectively by a compression spring 17 interposed between the said members. One of these slidable members consists of a metal disk 18 having a male contact tip 19 and a wire terminal sleeve 20 mounted thereon, both of the latter being insulated 1 from the disk 18 by an insulating bushing 21 and an insulating washer 22. A screw eye 23 threaded upon the rear end of the contact tip 19 coacts with the tapered bore of the sleeve 20 to wedgingly secure the bared end 24 of a cable 25, after the manner of the patent above cited. The other

slidable member consists of a flat metal ring or auxiliary annular member 26 with a bore considerably larger than the diameter of the male contact tip 19. Adjacent to the ring 26 and continuously pressed against the same by the spring 17, is a ring 27 of insulating material having on one of its faces a groove 28 adapted to receive one end of the spring 17.

10 When the two portions of the connector are approached as in Fig. —2—, the end of casing 1 will slide within that of the casing 13, the pins 14 entering the longitudinal slots 30 while the tip of the male contact 19 enters that of the female contact 6. As soon as the end of casing 1 abuts against the metal ring 26, the spring 17 will resist a further approaching of the two connector portions, but upon forcibly continuing this approaching, 15 the spring will be compressed, thereby permitting the ring 26 to recede until the projections 14 have reached the circumferential slot extensions 29. Then, upon slightly rotating the casings relative to each other, the 20 projections 14 will be turned out of alignment with the longitudinal slots and upon releasing the pressure forcing the connector parts toward each other, the spring 17 will coat with the rings 27 and 26 and the tip 25 of casing 1 to hold the said projections in the pockets 11. When the parts are thus interengaged or coupled, any pulling on the cables will only interlock them all the more firmly (instead of separating them as in 30 the case of frictionally interlocked contacts), while the continuous pressure of the spring will prevent the coupled portions from being disengaged by jarring. Moreover, by making the insulating ring 27 slightly larger in 35 bore than the diameter of the male contact tip 19, the latter may tilt slightly with reference to the axis of the casing 13, thereby allowing the interengaging male and female contact tips to aline in good contacting relation in spite of irregularities in the size or 40 shape of other portions of the two connector parts.

45 While I have shown the connector of my invention with the male contact tip spring mounted, and with a separable cap 28 covering the rear end of one of the casings, I do not wish to be limited to these particular arrangements, as many modifications might be made in the form illustrated without departing from the spirit of my invention.

50 I claim as my invention:

55 1. A wire connector comprising a pair of casings, one thereof equipped at one end with bayonet slots and slidably interfitting the bore of the other casing, the last-named casing equipped with projections extending radially inward thereof and entering the slots in the first-named casing when the two casings are approached, the bayonet formation of the said slots enabling the latter to

interlock with the said projections to couple the said casings; a wire terminal rigidly mounted within the casing having the slots and insulated therefrom; the casing having the projections being equipped at its other end with rigid stop formations; a disk housed by the last-named casing and normally bearing against the said rigid stop formations, a wire terminal carried by the said disk and insulated therefrom, and an annular member slidably mounted within the casing and interposed between the aforesaid disk and the said projections and normally bearing against the latter; and a spring interposed between the said disk and annular member and normally pressing the same respectively against the said rigid formations and the said projections; the opposed ends of the said wire terminals contacting with each other when the casings carrying the same are coupled, the flexibility of the said spring permitting the first-named disk to tilt about a portion of the said rigid stop formations normally interengaged thereby to move the terminal carried by the said disk laterally with respect to the axis of the casing housing the same, thereby enabling the said terminals to aline in good contacting relation; the said annular member abutting against the end of the casing having the slots and slidably moved by the said abutting engagement when the casings are forcibly approached to effect the said coupling; the said spring, disks and rigid projections coacting with the said abutting relation of the annular disk and the end of the slotted casing to tend to separate the said casings, the said tendency coacting with the said projections and the bayonet slot formations to hold the said casings in their said coupled relation.

2. A wire connector comprising a pair of casings, one thereof equipped at one end with bayonet slots and slidably interfitting the bore of the other casing, the last-named casing equipped with projections extending radially inward thereof and entering the slots in the first-named casing when the two casings are approached, the bayonet formation of the said slots enabling the latter to interlock with the said projections to couple the said casings; a pair of wire terminals respectively mounted within, and insulated from the said casings, the adjacent end of the said wire terminals contacting with each other when the casings are coupled; an annular member slidably mounted within the casing having the said projections and abutting against the end of the other casing when the casings are coupled; and a compression spring bearing at one end against a relatively stationary portion of the casing having the said projections and at its other end against the said annular member, the said spring and annular member coacting with the said

abutting to tend to separate the casings, the said separational tendency coöperating with the said slots and projections to maintain the casings coupled; the compressibility of the spring permitting the said annular member to be slidingly moved against the pressure of the said spring to permit the casings to be coupled or uncoupled; the said projections engaging the annular member to prevent the ejection thereof from the casing housing the same, when the casings are uncoupled.

3. A wire connector comprising a pair of casings equipped with relatively interengaging formations for coupling the same; a wire terminal mounted within each of the said members, the said terminals contacting with each other when the said casings are coupled, one of the said terminals being yieldingly mounted within the casing carrying the same for rendering the said terminal laterally movable relatively to the axis of the said casing, thereby permitting the said terminal to aline with the other terminal when brought into contacting relation therewith.

4. A wire connector comprising a pair of casings equipped with relatively interengaging formations for coupling the same; relatively slidably interfitting male and female contacts carried by the respective casings substantially axially of the latter, each of the said contacts insulated from the casing carrying the same; one of said contacts being yieldingly mounted within the casing carrying the same for rendering the said contact laterally movable with respect to the axis of the said last-named casing, the said

yielding mounting permitting the said contact to tilt into alinement with the other contact when the said casings are coupled.

5. In a device of the class described, a casing having an interior circumferential groove, an annular member seated in said groove and projecting inwardly beyond the bore of the casing, a member slidable within the said casing, a wire terminal mounted upon said slidable member, and means for holding the said slidable member against the said annular member.

6. In a device of the class described, a casing having an interior circumferential groove, an annular member seated in said groove and projecting inwardly beyond the bore of the casing, a member slidable within the said casing, a wire terminal mounted upon said slidable member and spring-actuated means for holding the said slidable member against the said annular member.

7. In a device of the class described, a casing having an interior circumferential groove, a detachable annular member seated in said groove and projecting inwardly beyond the bore of the casing, a member slidable within the said casing, a wire terminal mounted upon said slidable member, and means for holding the said slidable member against the said annular member.

In testimony whereof I have signed my name in presence of two subscribing witnesses.

GEORGE C. KNAUFF.
